N. Rider.
Spindle.

Patented Nov. 3, 1832.

Nathaniel Rides. Dudley, Mass.

Letter Patent

The Schedule referred to on the Letter Patent, and making part of the same containing a description in the Words of the said Nathaniel Rides himself of his improvement in the cotton spindle.

To all to whom these presents shall come. Whereas it is known that, at Nathaniel Rides of Dudley in the County of Worcester and Commonwealth of Massachusetts I have invented a new and useful improvement in the cotton Spindle which is commonly called the live spindle for spinning cotton yarn now in common use and that the following is a full and exact description of the construction and operation of the said improvement as invented or improved by me.

The improvement consists of a polished cylindrical tube or hollow spindle made of iron, steel or any other metallic substance either by drilling out the same or by buying from sheets - said tube or hollow spindle to be about six inches & five eighths of an inch in length and at the bottom part thereof to be about half an inch in the outer or external diameter and to continue the same diameter upward about one inch & one fourth of an inch and the remaining part of said tube upward to be about seven sixteenths of an inch in its external diameter. The internal or inner diameter of said tube is to be about $5\frac{1}{16}$ th of an inch at the top and $3\frac{1}{8}$ th of an inch at the bottom or the said tube or hollow spindle may be of any other diameter or dimensions to fit or apply it to the common spindle now in use and the said tube as constructed is to form a close but yet free collar at the top and is called of the common live spindle and the bottom part of said tube or hollow spindle enclosing the lower or neck of said live spindle extending through the cotton mass and on the live spindle but not so far as to rest or bear upon the lower portion of the live spindle. The collar now in use on

NOV 3, 1832

closing and confining the said tube or hollow spindle so that the said tube cannot turn within the same. This tube or hollow spindle is placed on the common line spindle as intended to be stationary and form a sheath over the common line and main spindle from its lower shoulder next above the airtight to the common spindle to the top shoulder where the flyers of said common spindle is placed as is usual on the bobbin or spool which receives the yarn as placed on & over the tube or hollow spindle in the same position or manner as it is usually placed on the common line spindle to receive the yarn rising and falling on said tube or hollow spindle as it does or then when wound on the common line spindle without the tube and then by means of the spool or bobbin running on the tube instead of the common line spindle a friction is created which gives the a main or more steady draft and there is more certainty of its receiving the yarn (especially upon an accelerated motion of the spindle) than when placed directly upon the line spindle in the usual manner. The washer instead of the one now in use on the common line spindle under the spool or bobbin should be of small dimensions and so small as to create the least possible friction & is to be made of sheet iron or any other metallic substance.

What I claim as new and as my own invention ordinary, in the above described tube or hollow spindle & for which & the use of which I ask an exclusive privilege is the particular form of the tube made and constructed of the material above named the manner of adjusting it to the common line spindle and the consequent operation of the spool while in the act of filling the metallic washer as before described.
